AIR LIFT PUMPING APPARATUS

Robert W. Scott, Chicago, Ill., assignor to Sullivan Machinery Company, a corporation of Massachusetts

Application September 30, 1935, Serial No. 42,774

9 Claims. (Cl. 103—232)

My invention relates to air lift pumping apparatus, and more particularly to so-called foot-pieces for such pumping apparatus.

An object of my invention is to provide an improved air lift pumping apparatus. Another object of my invention is to provide an improved foot-piece for an air lift pumping apparatus. A further object of my invention is to provide an improved aerating device for a column of liquid, which shall be of particular utility in sewage disposal plants and the like. A still further object of my invention is to provide an improved aerating device which shall be especially adapted to aerate relatively large columns and to effect the raising through short distances of relatively heavy liquids, and which in certain forms may be adjusted to provide aeration at different positions in the column of material to be pumped. Still another object of my invention is to provide an improved aerating device of the type mentioned, in which through the disposition of the orifices and the formation of the orifice carrying members, clogging due to the deposit of string or solid masses upon the aerating elements may be avoided. Other objects and advantages of the invention will hereinafter more fully appear.

In the accompanying drawings, in which one illustrative embodiment of a so-to-speak stationary foot-piece or aerating device is shown for purposes of illustration, together with three modified constructions embodied in adjustable type devices,—

Fig. 1 is a horizontal section on the line 1—1 of Fig. 2, through a foot-piece or aerating device.

Fig. 2 is a central vertical section through the foot-piece of Fig. 1.

Fig. 3 is a transverse section on the plane of section line 3—3 of Fig. 4, and Fig. 4 is a vertical central section, through a modified form of foot-piece or aerating device.

Fig. 5 is a transverse section on the plane of section line 5—5 of Fig. 6, and Fig. 6 a central vertical section, through a further modified form of adjustable foot-piece or aerating device.

Fig. 7 is a transverse section on the plane of section line 7—7 of Fig. 8, and Fig. 8 a vertical central section, through a still further modified form of construction.

Referring to the embodiment shown in Figs. 1 and 2 initially, it will be observed that a casing 1 is secured by suitable flange connections 2 and 3, respectively to a riser pipe 4 and to a supply pipe 5. It will be understood that normally the

liquid material to be pumped fills the supply pipe 5 and extends a substantial distance up in the delivery pipe 4, and that upon adequate aeration of the liquid in the zone between the supply and delivery pipes, the head which maintains the normal static level in the pipe 4 will cause a flow of the aerated and lightened column to a point of desired discharge. In the particular embodiment shown, the pipes 4 and 5 are of relatively large diameter, perhaps considerably more than a foot in diameter, and accordingly conventional forms of aerating devices or foot-pieces will not discharge sufficient air into the rising column of liquid to effect adequate lightening of the column to permit much pumping operation. It is accordingly necessary to provide a much more extensive aeration than with the ordinary riser line of a very few inches in diameter. To accomplish this aeration more effectually, there is provided within the casing 1, which has an enlarged circular portion 6 to provide an air chamber 7, an inner sleeve member 8 having cylindrical portions 9 and 10 respectively fitting the smaller portions 11 and 12 of the casing 1 which are respectively nearer the flange connections 2 and 3. Between the cylindrical portions 9 and 10 there is a bulged or enlarged wall portion 14 upon the member 8, this bulging being provided for a plurality of useful purposes. In the first place, the bulging offsets in some measure the reduction in flow area which will be understood to be caused by the presence of the auxiliary aerating means shortly to be described. In the second place, there is some—though perhaps not a very large—increase in the surface area through which the aerating passages may be formed.

The portion 14 of the member 8 supports a plurality of relatively narrow, radially inwardly projecting rib or fin-like portions 16, 17, 18 and 19, each of which is provided with relatively parallel walls 20 converging, as at 21, to form relatively sharp edges 22, the several edges 22 being spaced from each other near the center of the column. The aerating portions 16, 17, 18 and 19 are each formed with a curved bottom portion, the edges 22, which are relatively upright and parallel to the axis of the riser pipe at their upper portions, curving smoothly inwardly, as at 23, to merge into the lower cylindrical portion 12. The tops of the members 16, 17, 18 and 19 may be comparatively horizontal, and the upper portions of these members are desirably streamlined, as at 24, to provide a minimum interference with flow. By reason of the curvature, as at 23, the depositing and adherence of solid matter in the material

being pumped, upon the members 16, 17, 18 and 19 will be largely prevented, and cleaning will be made much less frequently necessary, while average efficiency of performance will be maintained 5 in a very desirable manner.

The aerating portions 16, 17, 18 and 19 each contain a space or chamber 26 in communication with the chamber 7, so that the interior of the portions 16, 17, 18 and 19 may be supplied with 10 air. The lateral walls and the curved walls 21 of these portions are perforated with jet openings 27 so that considerable quantities of air may be delivered very effectually into the different quadrants of the rising liquid column. There is further provided jet means 29 in the form of belts of jets extending circumferentially through the wall of the portion 14, and all of these jets also communicate with the space 7. It will therefore be noted that the rising column of liquid is subdivided 20 into a plurality of sector-like subdivisions and each of these subdivisions is provided with aerating means both along its bounding radii and along its bounding arc. Obviously, the orifices or jets 29 may be extended for greater or lesser vertical distances, as may be needed under the circumstances, and the number of subdivisions varied.

The mode of operation of this form of the invention will be readily understood from what has been said. As above noted, the material to be pumped will, in the absence of air supply to the chamber 7, fill the supply pipe 5 and the spaces within the aerating or foot-piece device, and extend upwardly a substantial distance into the delivery or riser pipe 4. Upon the supply of air to the chamber 7, the air will displace any liquid which may have attained access to the chamber 7 through the various jets 27 and 29, and the air will then discharge through the jets in a belt of 40 a width, vertically determined by the width of the field of orifices which has been formed in the wall 14 and in the aerating elements 16, 17, 18 and 19. The air will enter nearly all the parts of the liquid column and, because the aerating devices are 45 arranged as shown and described, there will be but little area in the complete cross section of the column which will not be reached by the air discharging through the various jets. As a result, the lightened column of liquid material will be 50 moved upward by the head available and the sewage or such other material as may be handled by this apparatus, will be delivered to the storage tank or vat or other point of delivery desired.

Assuming a column diameter of a foot, which 55 would be, as indicated, a small size for an aerating device of this character, it will be evident that a jet penetration of only a very few inches would be necessary completely to aerate the entire column. It will be noted, moreover, that due to the 60 shape of the curve at 23, and the narrowness and streamlining of the elements 16, 17, 18 and 19, flow will be interfered with to a minimum degree, and the possibility of solids becoming attached to 65 or sticking to the aerating device is greatly reduced.

Now referring to the other forms of the invention shown on the second sheet of the drawings, it will be observed that in each of the three species there illustrated the foot-piece or aerating 70 device is made vertically adjustable, in each case there being elongated sleeve-like portions 9' and 10' slidably arranged within cylindrical portions 11' and 12' with which the portions 9' and 10' have a close sliding telescopic fit. As a result 75 there will be possible a limited change in the

height of the foot-piece or aerating device, and since the static level of the material to be pumped is only a few feet in sewage disposal work, a relatively short vertical adjustment of the aerating device will provide substantial advantage in the 5 control of the pumping operation.

In the species illustrated in Figs. 3 and 4, it will be noted that the sleeve-like portions 9' and 10' are connected by an aerating portion 31 (generally cylindrical in cross section and having a 10 series of four web-like portions 32 extending inwardly into communication with each other, as at 33. The web-like portions have relatively horizontal tops 34, appropriately streamlined if desired, and upwardly tapering bottom portions 35, 15 also suitably streamlined if desired. Jets 36 are formed through the opposite walls of the portions 32, and also in the same horizontal zone circumferentially through the wall of the portion 31, as at 37. An adjusting rod 38 is connected, as at 39, 20 at about the point of juncture of the portions 32. It will be noted that the supply connection 40 opens into a longer chamber 7' in the casing 6', and that a vertical adjustment of from some inches to a foot or more is possible, depending 25 upon the relative length of the telescopic connections at 9', 11' and 10', 12'. This form of the invention has the advantage of the adjustability of the foot-piece or aerating device, but is, because of its construction, less free, somewhat, 30 from the possibility of having string or other solid matter adhere to and interfere with the operation of the aerating device.

In Figs. 5 and 6, instead of having four quadrantly arranged portions 32, a diametrically extending portion 42 having discharge orifices 43 is provided, and at its center the foot-piece is provided with a suitably streamlined chamber portion 44, whose arcuate walls in the spaces between the junction therewith of the portions 42 40 are traversed by orifices 45. The elevating rod 46 is connected, in this form, to the top of the streamlined member 44. Aside from these particular differences, the arrangement is quite similar to that of Figs. 3 and 4.

In Figs. 7 and 8 a further arrangement is shown. This form includes an elevating rod 49 connected at 50 to a bridge element 51 which extends across the vertical bore provided by the inner wall 52 of an annular mixing chamber 53 spaced radially inward from the outermost belt 54 of orifices and supported by a pair of diametrically opposite, relatively narrow, short support and aerating portions 55. It will be noted that the bottom of the member 53 is suitably formed, 55 as at 56, to reduce flow resistance, and that the top is streamlined, as at 57, further to reduce flow resistance. It will be noted that the outer wall 58 of the portion 53 is traversed by orifices 59, while the inner wall 52 is traversed by orifices 60. Accordingly, this device will break up the rising column of liquid into a central column passing through the member 53 and an annular column broken by the members 55 passing through the otherwise annular space 61 between the wall 58 and the wall traversed by the orifices 54. This form of apparatus will obviously provide a very thorough aeration of the rising column, for the radial dimension of the central rising column may be made comparatively 70 small, and the annular zone 61, being aerated from both its inner and outer sides and also chordially in the portion 55, will be most effectively aerated.

It will be obvious that in all the forms of my 75

invention thoroughly reliable and rugged aerating devices or footpieces are provided. In some, provision for vertical adjustment is made. In all, streamlining is resorted to to such extent as may be most advantageous. In all, there is at least one annularly extending belt of aerating orifices. In all, there are at least some radially extending aerating portions. In some, sectorial division of the rising column is practiced; while in others the form of an annular rising column—in one instance with a central column also—is disclosed; and in all cases a most effective aeration is insured by extremely short (compared with the transverse dimension of the riser pipe) travel of aerating fluid.

While I have in this application specifically described one form which my invention may assume in practice, and three modifications thereof, it will be understood that these are shown for purposes of illustration, and that the invention may be further modified and embodied in various other forms without departing from its spirit or the scope of the appended claims.

What I claim as new and desire to secure by Letters Patent is:

1. In an air lift aerating device, means forming an air chamber and having a wall generally circular in cross section separating said chamber from and forming a passageway for a rising liquid column, a belt of aerating orifices traversing said wall, and radially extending portions connected to said wall and having relatively parallel walls between which are chambers communicating with said air chamber and through which relatively parallel walls extend orifices opening into the rising liquid column.
2. In a foot-piece, a casing providing a chamber, an internal member within said chamber providing a wall and cooperating with the casing to provide an annular space to which aerating fluid may be admitted, a plurality of orifices through said wall, and means within the confines of said wall providing aerating means projecting radially into the space surrounded by said wall and having upwardly inclined bottom portions whose highest portions are most adjacent the center of said foot-piece, to facilitate flow.
3. In a foot-piece, means forming an annular belt of air orifices, and means providing a plurality of radially extending aerating devices extending inwardly from said first mentioned means and having aerating orifices discharging at right angles to their radial directions.

4. In a foot-piece, aerating means dividing a column of liquid to be aerated into four quadrant subdivisions and having orifices arranged to discharge into said subdivisions along both bounding radii and along the arc thereof.

5. In an air lift foot-piece, means providing an annular belt of aerating orifices, and communicating means providing a diametric zone of aerating orifices, said last mentioned means having between its ends means providing an enlarged chamber having orifices arranged in the walls thereof and discharging radially outwardly.

6. In an air lift foot-piece, means providing an annular belt of aerating orifices, and communicating means providing a diametric zone of aerating orifices, said last mentioned means having between its ends means providing an enlarged chamber having orifices arranged in the walls thereof and discharging radially outwardly.

7. In an air lift aerating device, means forming an air chamber including a wall generally circular in cross section separating said chamber from and forming a passageway for a rising liquid column, a belt of aerating orifices traversing said wall, and radially extending portions connected to said wall and having radially extending walls bounding chambers communicating with said air chamber and through which radially extending walls are formed orifices opening into the rising liquid column.

8. In a foot piece, a casing providing a chamber, and an internal member within said chamber casing cooperating with the latter to provide an annular space to which aerating fluid may be admitted, said internal member comprising portions forming a peripheral wall and hollow fin-like portions extending inwardly from the peripheral portions of said internal member and tapering in radial dimension from a maximum inward projection at their tops to merge into said wall at their lower ends, said fin-like portions having their interiors communicating with said annular space and having aerating orifices in their lateral walls.

9. In a foot piece, means for confining and guiding a rising column of liquid, and means for admitting thereto an aerating fluid including orificed surfaces extending in directions at right angles to each other and an arcuate orificed surface to which said right angularly arranged surfaces are normal.

ROBERT W. SCOTT.

CERTIFICATE OF CORRECTION.

Patent No. 2,062,799.

December 1, 1936.

ROBERT W. SCOTT.

It is hereby certified that error appears in the printed specification of the above numbered patent requiring correction as follows: Page 2, first column, line 19-20, for "subvided" read subdivided; and second column, line 9, after the numeral "31" insert a comma and strike out the parenthesis before the syllable "gener-"; page 3, second column, line 32-33, claim 8, strike out the word "chamber"; and that the said Letters Patent should be read with these corrections therein that the same may conform to the record of the case in the Patent Office.

Signed and sealed this 19th day of October, A. D. 1937.

(Seal)

Henry Van Arsdale
Acting Commissioner of Patents.
